DESIGN.

—o—
H. SMITH.

HEATING STOVE.

No. 17,579.

Patented Aug. 2, 1887.

UNITED STATES PATENT OFFICE.

HOLMES SMITH, OF ST. LOUIS, MISSOURI.

DESIGN FOR A HEATING-STOVE.

SPECIFICATION forming part of Design No. 17,579, dated August 2, 1887.

Application filed June 21, 1887. Serial No. 242,042. Term of patent 14 years.

To all whom it may concern:

Be it known that I, HOLMES SMITH, a British subject, residing in the city of St. Louis, Missouri, have invented and produced a new and original Design for Heating-Stoves, of which the following is a specification, reference being had to the annexed engraving, forming part thereof, and showing the newly designed stove in perspective.

- 10 The body a of the stove A is, considered generally, a rectangular prism, having projections a' at its ends. It rests upon a rectangular base-plate, a^2 , which in turn is unsupported upon the legs a^3 . The top plate, a^4 , overhangs the body, and it is crowned and hipped. The lower portion, a^5 , of the top plate is terraced and has a smooth finish, and upon the upper portion of the top plate a tracery appears. An urn, a^6 , terminates the structure.
- 15 The leading feature of the design is the frettile pattern B, of a Moorish character, appearing throughout the body of the stove and also upon the top plate, substantially as shown. The legs bear the scallop C, inclosed in the
- 20 border c. The stem and base of the urn a^6 may be said to have an hour-glass shape. The wall

of the urn-bowl is nearly vertical, and it is fluted vertically, and the lip of the bowl overhangs the wall and is scalloped.

I claim—

1. The design for a heating-stove herein shown and described; the same consisting of the rectangular body resting upon the rectangular base and having an overhanging crowned and hipped top plate surmounted by an urn, the whole having the shape and ornamentation shown. 30
2. In a design for a heating stove, the design herein shown and described, the same consisting of the interlaced fret-tile pattern 40 upon the stove-body.
3. In a design for a heating-stove, the design herein shown and described, the same consisting of the rectangular body with the crowned and hipped top plate, the tracery described appearing upon both said body and said top plate. 45

HOLMES SMITH.
